(57) **CLAIM**

The ornamental design for a rectangular handbag, as shown and described.

DESCRIPTION

FIG. 1 is a right front elevational perspective view of a rectangular handbag showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The subject handbag is ornamented with a plurality of protrusions from the surface thereof, as shown.

The "Dior" trademarks forming part of the claimed design are owned by Christain Dior Couture S.A.
